UNITED STATES PATENT OFFICE.

FRANK J. DUNN, OF ELMIRA, NEW YORK.

RAPID-REFERENCE RECORD.

Application filed September 29, 1925. Serial No. 59,273.

This invention relates to new and useful improvements in a rapid reference record.

The primary object of the invention is to provide a record by means of which a rapid reference may be made to any number, preferably having from one to five digits, but being capable of use with numbers having as many as seven digits if desired.

A further object of the invention is to provide a record which employs numbers as its reference characters, said numbers being used to represent or distinguish any desired objects, such as railway rolling stock, machinery, articles of a stock in trade, workmen in a factory, a shop, or a workhouse, drivers or automobile licenses, etc.

A still further object of the invention is to provide a record of the above mentioned type which will enable the person or persons keeping the same to enter under any given number a fact or series of facts relating to the particular object represented by that number and without necessitating the recording or filling in of any of the digits of the reference number with the entry.

Other objects and advantages of the invention will be apparent during the course of the following description.

In the accompanying drawings forming a part of this specification, and in which like numerals are employed to designate like parts throughout the same.

Figure 1 is a plan view of three units which form a part of the complete record,

Figure 2 is a plan view of one of the units and shows a portion of the sheets of this unit spread out in fan style to illustrate the presence of a plurality of the same,

Figure 3 is a plan view showing in detail one of the record sheets of a unit, and

Figure 4 is a fragmentary edge elevational view, partly in section, of one of the record units.

Briefly described, this rapid reference record is divided into one hundred units with each unit being designated by a master or key number ranging from double zero to ninety-nine. Each unit is further divided into ten cards with each card bearing a reference number ranging from zero to nine. To further divide the record, each card is divided into ten sections and each section is referred to or distinguished from every other section by a number ranging from zero to nine. Each section of a card is separated into two divisions with one division pro-

vided with ten columns which are designated by reference numerals ranging from one to nine, the right hand column being left blank and representing zero, the remaining division of each section being divided into columns if desired or left perfectly blank if the particular entries to be made upon the same require no further divisions.

In the drawings, wherein for the purpose of illustration is shown a preferred embodiment of this invention, the numeral 5 is employed for designating in its entirety a complete unit of this record. Each unit is designated by a master or key number 6 which may be displayed thereon in any desired manner. This complete record includes one hundred units which are designated by master or key numbers ranging from double zero to ninety-nine, the three units bearing 75 the master or key numbers 00, 98, and 99 being illustrated in Fig. 1. It is obvious that the remaining ninety-seven units, not shown in Figure 1 will have key numbers of like character ranging from 00 to 96 inclusive 80 but it is not deemed necessary here to show each of these units.

Figures 2 and 4 clearly illustrate a unit 5 as including separate cards 7 which are separably connected together, in any desired 85 manner, such as by a staple or rivet 8. It will be noted that Fig. 2 illustrates the unit 5 bearing the master or key number 97 and it will be seen that each card 7 of a unit is marked or provided with the master or key 90 number designated by the reference character 6. Figure 2 clearly shows each card as being formed with a top margin 9 with each top margin of the various cards 7 of a unit varying in length to provide ends upon 95 which the reference digits 10 may be placed in a manner so that every reference digit 10 may be seen at one time when a unit is arranged with its various cards registering at their three remaining edges with each other, 100 as illustrated in Fig. 1. It will be noted that these reference digits 10 range from zero to 9.

Reference should now be made to Fig. 3 wherein there is shown one of the cards 7 of the unit bearing the master or key number 97, this particular card 7 being the zero card of this unit. It should first be noted that each card is ruled to form the lines 11 which extend from side to side of 110 the card and most of which are employed for writing entries thereon to separate one

entry from another. The card is further provided with the double rulings 12, 13 and 14 which extend from the top to the bottom of the card. These double rulings 12 to 14 divide the card into four main columns with the double ruling 13 dividing the card from top to bottom into two different parts, with each part halved by the double rulings 12 or 14. At equi-spaced points, the lines 11 are made extra heavy, as at 11^a, and these heavy lines 11^a divide each part of the card into sections 15 which are outlined by the double ruling 13 and the heavy lines 11^a. The double rulings 12 and 14 will be seen to further divide each section 15 into separate divisions 16 and 17. The division 16 of each section 15 is divided into ten columns by the lines 18 which intersect each of the lines 11 and also divide the line 20 occurring between the heavy rulings 11^a. Each column 19, formed by the lines 18, is provided with a reference numeral 20 and these reference numerals 20 run from 1, which designates the left-hand column, to 25 blank or zero which represents the right-hand column, the columns in between being referred to by the numerals 2 to 9.

It will now be seen that each section 15 is provided with a four-digit reference numeral 21 which has as its last two digits the master or key number 97 which is referred to by the reference character 6 and appears upon the particular card being described. The third digit from the right in each of these numbers 21 ranges from zero to nine, thereby distinguishing the ten different sections 15 of the card.

The manner of making an entry in this record will now be explained. It will be considered that this first entry relates to the location of a particular freight car or engine belonging to the railroad keeping this record. We will give the car the designating number 50,097. We must determine first the unit 5 in which this number may be found. The last two digits of the number constitute the master or key number and it will be seen that the master or key number of this car number is 97. We then locate the unit 5 bearing the master or key number 97. After locating the proper unit, we must then determine which card to refer to and the second digit from the left is employed to designate the particular car. This number 50,097 has zero for its second digit from the left and for this reason we must now refer to the card 7 having in its top margin 9 the reference numeral zero. We find that this particular card is shown in detail in Fig. 3. We must now determine which one of the ten sections of this card is to be used and the third digit from the right, or the digit appearing immediately in front of the master or key number 97 is used. This number 50,097 has for its

third digit from the right the number zero and this refers us to the upper left hand section 15 of the card. We now have one digit left in the car number and this is the first digit which is five. We now refer to 70 the ten different columns appearing in the division 16 of this upper left hand section 15 and locate the column bearing the reference numeral 5. The entry should then be made on the first vacant line, provided by 75 the lines 11, starting the entry in the column 5. We will make an entry which will show that the car number 50,097 is located on the Baltimore & Ohio tracks, Division 3, and this entry may be abbreviated by writing 80 B & O No. 3. To further illustrate the locating of a number, which number we will consider as the means employed for distinguishing a workman by the name of John Doe, we will use 90,997 as the number to 85 be located. The last two digits, 97, furnish us with the master or key number of the workman and refers us to the unit bearing the master or key number 97. The second digit from the left of this number is zero 90 and that refers us to the particular card shown in Fig. 3 which is the zero card of the unit bearing the master number 97. The third digit from the right of this number is nine and that refers us to the section 9 95 appearing at the lower right-hand corner of the card. The one remaining digit, the first one of the number is seen to be nine and we make our entry starting with column number 9, the entry being Doe, John.

It is now believed that the method of quickly or rapidly referring to any particular number will be clearly understood however, it will be noted that the numbers so far referred to only have five digits. Should we have a number with six digits, it is referred to in the following manner. We will employ the first referred to number of 50,097 and will add the digit 8 to the front of the same, making the number 105 850,097. Without following the various digits of this number to locate the particular unit, card, and section, as this has already been done in connection with the number 50,097, we will immediately refer 110 to the upper left-hand corner of the card shown in Fig. 3. The added digit 8 is not referred to during the locating of the particular division in which the entry starts and the number is considered as having only 115 five digits, the first five digits starting from the right being used. This locates us in the same column as the entry referring to the car numbered 50,097 and we first insert the number 8 in this column bearing the reference numeral 5. This gives us the number 120 850,097 and immediately after the number 8 we start in with the entry, which we will consider is Erie No. 5, January 16, 1924.

To briefly refer to the advantages set 125 130

forth in the use of this rapid reference record, attention is first invited to the provision of the different independent units which may be handled by many different 5 people working on the record at any one time, that is, one person might be making entries in the unit bearing the master digit 99 while somebody else could be working on the unit bearing the digit 97, etc. This provision of separate units is considered as an 10 improvement over binding all of the cards into one book. The loose leaf formation of a unit will enable new cards to be inserted at any point in a unit should a card be 15 filled. This is also an advantage that cannot be found in binding the cards in a book. A further point worthy of noting is that with numbers having from one to five digits, none of the digits of the number need 20 be written in the record when an entry is made.

It is to be understood that the form of this invention herewith shown and described is to be taken as a preferred example of the same, and that various changes in the shape, size, and arrangement of parts may be resorted to without departing from the spirit of the invention or the scope of 25 the subjoined claims.

Having thus described the invention, I claim:—

1. A record of the type described comprising, a series of units capable of being independently handled, a master number for each unit, each unit comprising ten cards which are bound together in loose leaf form, an exposed tab on each card which bears a number ranging from zero 30 to nine, each card being divided into ten sections by intersecting rulings running from top to bottom and side to side

thereof, and further rulings extending from top to bottom of the cards for dividing each section into two divisions. 45

2. A record of the type described comprising, a series of units capable of being independently handled, a master number for each unit, each unit comprising ten cards which are bound together in loose leaf form, an exposed tab on each card which bears a number ranging from zero to nine, each card being divided into ten sections by intersecting rulings running from top to bottom and side to side thereof, the sections being consecutively numbered from zero to nine, further rulings extending from top to bottom of the card for dividing each section into two divisions, and one of said divisions being ruled to provide ten columns 50 with the columns consecutively numbered one to nine, the right-hand column indicating zero. 55

3. A record of the type described comprising, a series of units capable of being independently handled, a master number for each unit, each unit comprising ten cards which are bound together in loose leaf form, an exposed tab on each card which bears a number ranging from zero to nine, each card being ruled from side to side to form writing lines with pairs of adjacent rulings at equi-spaced intervals heavier than the other rulings to form the card 60 into equal parts, double rulings extending from top to bottom of the card for dividing the parts into divisions, and two divisions in each part being divided into ten columns by lines extending from top to bottom of the card. 65

In testimony whereof I affix my signature.

FRANK J. DUNN.
